UNITED STATES PATENT OFFICE.

LESTER H. ALLEN, OF FARMINGTON, NEW HAMPSHIRE, ASSIGNOR OF ONE-HALF TO ALONZO I. NUTE, OF SAME PLACE.

TRIMMING ATTACHMENT FOR SEWING-MACHINES.

SPECIFICATION forming part of Letters Patent No. 246,860, dated September 13, 1881.

Application filed May 2, 1881. (No model.)

To all whom it may concern:

Be it known that I, LESTER H. ALLEN, of Farmington, county of Strafford, State of New Hampshire, have invented a new and useful 5 Improvement in Trimming Attachments for Sewing-Machines, of which the following description, in connection with the accompanying drawings, is a specification.

This invention in sewing-machines has for 10 its object improvements in apparatus for trimming scalloped or other edges of leather or other material used in the manufacture of boots and shoes and other articles.

My invention has for its object the production of a trimming attachment which may be 15 readily thrown out of or into operative position with relation to the needle and shuttle which form the stitch, so as to trim the edge as each stitch is made, or permit the stitching to proceed without trimming, as when turning corners or in sharp angles of scallops. This provision of discontinuing the operation of the cutter enables scallops with sharp corners to 20 be trimmed at a uniform distance from the row 25 of stitches, notwithstanding the shape of the scallop.

The devices which control the time of operation and rest of the cutter-bar are located close to the fly-wheel, connected with the main shaft 30 of the sewing-machine, upon which fly-wheel the operator, when stitching curves or irregular lines of stitching, usually retains his hand. Such location of the said devices enables the operator, with the same hand with which he 35 starts and stops the machine, to throw the cutter-bar at will into and out of operation at any stitch.

Figure 1 represents, in front elevation, a sufficient portion of a Weed sewing-machine with 40 the face-plate removed to illustrate one embodiment of my invention. Fig. 2 is a side elevation thereof, the face-plate having been applied. Fig. 3 is a section on dotted line xx , Fig. 2, looking toward the left. Fig. 4 is an 45 enlarged detail, showing the lower end of the cutter-bar and cutter and needle-bar and needle. Fig. 5 is a detail top view of the slotted throat-plate through which the needle and usual feeding-bar and cutter work. Fig. 6 represents a scallop such as may be trimmed with 50

the trimming attachment herein described, and Fig. 7 is a top view of the lever m .

The sewing-machine selected upon which to illustrate my invention is a Weed sewing-machine, the construction of which is so well known as not to need a detailed description, further than that d is the main shaft, on which are the fly-wheel f and eccentric c^2 . The eccentric reciprocates the link e , and the latter, connected with the pin a^4 (shown in section, Fig. 60 3) of the arm a^5 of the rocker-shaft a , rocks the said shaft and actuates the needle-bar, all as usual.

Within the head of the sewing-machine, at the front end of the goose-neck, I have placed 65 the cutter-bar g , to the bent lower end of which I have secured the cutter h . This bar g is slotted at 2 to receive the fulcrum-pin 3, fixed to the head of the machine. The bar g , near its upper end, is cut away, as represented at 4, to 70 prevent interference with the usual screw, which, inserted in the hole 5, (see Fig. 1,) holds the upper end of the face-plate i of the head in position.

The spiral spring j , connected at its upper 75 end with the head of the machine and at its lower end with the bar g , as shown in dotted lines, Fig. 1, acts to lift the said bar into the position shown therein whenever the said bar is not positively depressed by the action of 80 the needle-holding screw or nut k (see Fig. 2) extended backward from the needle-bar, which screw or nut strikes the curved or bent lower end of the cutter-bar. This bar g , at its upper end, is engaged by the forward end of 85 the lever m , it having, as herein shown, a loop, l , into which the upper end of the said bar is entered. The lever m has its fulcrum at m' , and near its rear end it is provided with a suitable loop, m^2 , or opening, to receive the upper end of a T-shaped lever, n , having its fulcrum at n' , and provided with depending legs n^2 n^3 , which are extended through a slot in a shipper-slide, n^4 , adapted to be moved in one direction by a cam-shaped hand-lever, n^5 , pivoted thereon, and held pressed against the upright part c^2 of the frame by means of a coiled or spiral spring, n^6 , surrounding the said shipper-slide. 90

Upon the connecting-rod e I have adjusta- 100

bly secured a striker, *o*, adapted to strike the lower end of one or the other of the two legs *n*² *n*³, according to the position of the shipper-slide *n*⁴ as the link rises, such operation turning the T-shaped lever *n* in one or the other direction and vibrating the lever *m* to cause its forward end, embracing the cutter-bar, to swing or vibrate the latter about the fulcrum-pin 3, to either place the lower bent end of the cutter-bar *g* in range with or remove it out of range of the needle-holding nut or screw. When the shipper-slide is moved into its farthest position toward the head of the machine, as represented in full lines, Fig. 2, the rear-most leg, *n*², will be struck by the striker *o* and the T-shaped or three-armed lever, and the lever *m* will then be moved so as to place the cutter in operative position, as shown in full lines, Figs. 1 and 4; but as soon as the hand-lever *n*⁵ is turned, as in dotted lines, and the shipper-lever *n*⁴ is moved back to bring the leg *n*³ in line with the striker *o*, then the T-shaped lever *n* and lever *m* will be so shifted or moved as to place the cutter-bar in the dotted-line position, Fig. 1, removing its lower bent end out of the range or reach of, and so that it will not be struck and operated by, the needle-holding screw or nut *k* in the descent of the needle-bar. With the parts in such position the cutter will cease to operate; but the stitching may be continued for any number of stitches. This cutter-bar may be thrown out of or into operation at any stitch, and be continued in or out of operation for any number of stitches.

It is of great importance in the practical operation of a trimming device having the mode of operation herein described that the hand-lever or device for throwing the cutter into and out of action be so located with relation to the hand or fly wheel *f* that the operator, with his right hand, which is usually kept on the fly-wheel, may readily and with but a slight movement of the hand, reach the device *n*⁵, a slight movement of which determines whether or not the cutter shall be operated to do trimming.

The mechanism herein shown is very simple in construction, yet I do not desire to limit myself to the exact construction herein shown, as the shape of the levers for throwing the cutter-bar and blade or cutter *h* into and out of operation may be changed without departing

from my invention. The cutter *h*, made as a short blade with a beveled end, is caused to descend into the small slot *p* in the usual throat-plate *r*.

In Fig. 6, *s* represents a piece of leather, *u* the sharp-angled scallops, and *t* the line of stitches.

60

I claim—

1. The pivoted vertically-reciprocating cutter-bar, its cutting-blade, the reciprocating needle-bar to move the cutter-bar in one direction, and a spring to move it in an opposite direction, combined with a lever in engagement with the cutter-bar at one side of its fulcrum, said lever being adapted to turn the cutter-bar upon its pivot to place it into or remove it out of position to be actuated by the descent of the needle-bar, substantially as described.

2. The pivoted vertically-reciprocating cutter-bar, spring to lift it, the lever to engage and vibrate the cutter-bar to place its lower end in range or remove it out of range of a projection or device on the needle-bar, and a three-armed lever having legs pivoted thereto, combined with means to control the position of the legs and a striker to operate upon one or the other of the said legs, as and for the purpose described.

3. In a trimming attachment for sewing-machines, a vertically-reciprocating cutter-bar, a lever in engagement therewith to throw the cutter-bar into and out of operative position, combined with a cutter-controlling lever located and arranged at the rear end of the sewing-machine, near the fly-wheel, and with intermediate mechanism to automatically operate the lever which throws the cutter-bar into or out of operative position after the controlling-lever is shifted as to its position, substantially as described.

4. The lever *n*⁵, T-shaped lever, its legs, and the movable shipper-slide, lever *m*, and cutter-bar and cutter, combined with the striker connected with the link *c*, substantially as described.

In testimony whereof I have signed my name to this specification in the presence of two subscribing witnesses.

LESTER H. ALLEN.
